UNITED STATES PATENT OFFICE.

ADOLF LANGEN, OF COLOGNE, GERMANY.

GAS-GENERATOR.

SPECIFICATION forming part of Letters Patent No. 726,949, dated May 5, 1903.

Application filed February 16, 1903. Serial No. 143,705. (No model.)

To all whom it may concern:

Be it known that I, ADOLF LANGEN, manager, a subject of the German Emperor, residing at 14 Von Werth strasse, Cologne-on-the Rhine, Germany, have invented certain new and useful Improvements in Gas-Generators; and I do hereby declare the following to be a full, clear, and exact description of the invention, such as will enable others skilled in the art to which it appertains to make and use the same.

My invention relates to an improvement in gas-generators in which the air required for combustion is sucked into the generator by the aspirating action of the gas-engine. As the ash-box must be open to the air in this form of generator and gas continues to be developed for a short time after the stopping of the engine, it escapes through the grate and forms an explosive mixture with the air, which coming into contact with the red-hot coals by diffusion or by being sucked into the generator when the engine is again started takes fire and explodes with a loud detonation.

The present improvement is intended to avoid this inconvenience and danger by placing a sucking-valve in the air-conduit and a back valve in the gas-conduit leading to the engine.

In the accompanying drawings I have shown by way of example in Figures 1 and 2 two different embodiments of my improved generator.

Referring to Fig. 1, A is the generator. b is the air-conduit, with the sucking-valve c, and d the gas-conduit, with the back valve e. Both valves remain closed as long as the pressure is equal on both sides. When, however, the engine aspirates, the valve e is kept shut by the pressure of the atmosphere and the valve c opens automatically and admits air into the generator, where it is converted into gas. When the engine is stopped, valve c closes immediately and valve e opens to the pressure produced by the continued development of gas and allows the surplus to escape into the air. Thus no combustible gas can issue from the generator into the ash-box, and the explosions caused thereby are avoided.

Fig. 2 shows a preferable form of the sucking-valve adapted for generators in which the

current of the air for combustion is conducted over heated water before entering the furnace. This water-level may be utilized as a back valve by making the water vessel airtight and conducting the current of air through the water by placing the mouth of the conduit below the surface, thus forming a water trap which acts as a back valve.

Referring to Fig. 2, it will be seen that a is an evaporating-tank arranged above the generator A and warmed by the hot gases. The air-conduit b is fixed in the tank a and reaches down below the surface of the water, which is kept at a constant level by means of a supply-pipe and an overflow. (Not represented in the drawings.) In the gas-conduit a back valve e is provided in the same manner as in Fig. 1, which opens to the pressure of the gas from within and may of course be also replaced by a water trap.

When the engine is started and a partial vacuum is produced by its aspirating action, air will enter through the conduit b and through the water into pipe c. The air, which has already taken up moisture from the water, is saturated with vapor on its way through the evaporator a and is then sucked into the furnace of the generator.

I of course do not limit myself to the details of this generator as described. A boiler may also be arranged independently of the generator as an evaporating-tank and heated by the hot vapors. The described water trap has the advantage that it does not require any special parts, but can be formed by means of the necessary parts of the generator.

Having now particularly described and ascertained the nature of my said invention and the manner in which the same is to be performed, I declare that what I claim is—

1. In a generator from which the gas produced is aspirated by a gas-engine the combination of an ash-box, of an air-conduit leading into the ash-box, of a suction-valve in the air-conduit, of a gas-conduit and of a back valve in the gas-conduit substantially as described and for the purpose set forth.

2. In a generator from which the gas produced is aspirated by a gas-engine the combination of an ash-box, of an air-conduit leading into the ash-box, of a water trap in the air-conduit, of a gas-conduit and of a back

valve in the gas-conduit, substantially as described and for the purpose set forth.

3. In a generator from which the gas produced is aspirated by a gas-engine the combination of an ash-box, of an air-conduit leading into the ash-box, of a water trap in the air-conduit and formed by a tank surrounding the generator, of a gas-conduit and of a

back valve in the gas-conduit, substantially as described and for the purpose set forth.

In testimony whereof I have affixed my signature in presence of two witnesses.

ADOLF LANGEN.
